UNITED STATES PATENT OFFICE

RENÉ G. HARE, OF ARDMORE, PENNSYLVANIA

ELECTRIC HEATING UNIT

Original application filed February 26, 1929, Serial No. 342,759. Divided and this application filed January 14, 1930. Serial No. 420,673.

My invention relates to an electric heating unit adapted to form the component part of a device such, for example, as a necktie press or the like.

The principal object of my present invention is to provide an electric heating unit which will be simple, durable, and efficient, and which may be inexpensively constructed, and which may be readily fabricated by persons of relatively little skill.

The nature and characteristic features of my invention will be more readily understood from the following description, taken in connection with the accompanying drawing forming part hereof, in which:

Figure 1 is a plan view illustrating an early stage in the formation of an electric heating unit embodying the main features of my present invention;

Fig. 2 is a similar view of an intermediate stage;

Fig. 3 is a similar view of a heating unit in the final stage of its fabrication, ready to be incorporated in the apparatus in which it is intended to be used, as, for example, a necktie press;

Fig. 4 is an enlarged transverse sectional view of the heating unit, the section being taken on the line 4—4 of Fig. 3;

Fig. 5 is a plan view of a device used for securing the ends of the heating wires to the lead-in wires, which device is also adapted to assist in the connection of the wires to each other, the lead-in wires being shown in operative relationship therewith;

Fig. 6 is a perspective view, slightly enlarged, of the device shown in Fig. 5, but without the wires associated therewith;

Referring to the drawing, the heating unit there shown comprises preferably three sheets, 15, 16, and 17, of asbestos or similar insulating material. Arranged between the sheets 15 and 16 is a resistance wire 18, which beginning near one of the corners, extends preferably longitudinally back and forth, and ends at another corner.

The sheets 15 and 16 are united to each other by means of a suitable cement 19, such as water glass or silicate of soda solution, in which the wire 18 is imbedded when the same

sets. The sheets 16 and 17 are also united to each other by a cement 20, in a similar manner.

The sheet 16 is preferably made shorter than the sheets 15 and 17, so as to provide a pocket in which a member 21, preferably made of a sheet of vulcanized fibre or the like, is positioned. The member 21 is provided near its central portion with two holes 22 and 23; also two holes 24 and 25, located short distances from the holes 22 and 23 respectively. The member 21 is also provided near its respective end portions with struck up tabs or tongues 26 and 27.

The electrical energy for heating the unit is supplied by a suitable cable 28, comprising a pair of insulated wires 30 and 31. The wire 30 extends through the hole 22, from one face to the other of the member 21, thence through the other hole 24, beyond which the insulation is removed, and the wire bent back in hook-like form as at 32.

In like manner, the wire 31 extends through the holes 23 and 25 of the member 21, and likewise has the insulation removed from its end, and the same bent over in hook-like form as at 33.

One end of the resistance wire 18 extends under the tab or tongue 26 of the member 21, and is then wrapped or coiled around the bared and hook-like end of the wire 30. In like manner, the other end of the resistance wire extends under the tab or tongue 27 of the member 21, and is similarly joined to the bared and hook-like end of the wire 31.

The member 21, and the wire ends associated therewith as hereinbefore set forth, are imbedded in the cement which secures the same in place in the pocket between the ends of the sheets 15 and 17, said pocket being provided by reason of the sheet 16 being shorter than the sheets 15 and 17.

In fabricating the heating unit the sheet 15 is first placed upon a suitable table, such, for example, as that of the machine of my invention, described in my application for Letters Patent filed February 26, 1929, Serial No. 342,759, of which this application is a division, being located by means of two groups of pins, one group 35 penetrating the

sheet near one end thereof, and the other group 36 penetrating the sheet near the other end thereof.

The resistance wire 18 being secured at one end to a suitable clamping post 37, is then arranged on top of the sheet by means of the two groups of pins 35 and 36, extending longitudinally back and forth over said sheet 15, and around said pins 35 and 36, and finally being secured to another clamping post 38 (see Fig. 1).

The sheet, with the wire arranged thereon as above described, is now coated with a suitable cement, such as water glass or the like. The sheet 16 is then placed over the sheet 15 with the wires and cement thereon, and is clamped against the same, the pins 35 and 36 penetrating the sheet 16, and the parts being held clamped together until the cement sets.

As before noted, the sheet 16 is somewhat shorter in length than the sheet 15, and in the space thus provided the member 21, with the ends of the wires 30 and 31 secured therein as hereinbefore described, is placed in position upon the end of the sheet 15 which projects beyond the end of the sheet 16.

The ends of the heating wire 18, being released from the clamping posts 37 and 38, are brought under the respective struck up portions 26 and 27, after which they are coiled around the bared hook-like ends of the wires 30 and 31, to establish an electrical connection therewith.

The pins 35 and 36 having meanwhile been withdrawn, the exposed surface of the sheet 16, as well as the member 21 and the parts associated therewith, are coated with the cement, after which the sheet 17 is placed thereon and clamped in position until the cement sets. The heating unit, after the cement has set, is then ready for incorporation in the article (such as a necktie press or the like) in which it is to be used.

It will be seen that there is thus provided an electric heating unit of novel construction and arrangement, which may be readily and expeditiously made at a minimum of expense.

It will, of course, be understood that various changes and modifications may be made without departing from the spirit of my invention.

Having thus described the nature and characteristic features of my invention, what I claim as new and desire to secure by Letters Patent, is:

1. An electric heating unit comprising three thin flat rigid sheets of insulating material cemented to each other, a resistance wire extending back and forth between two of said sheets and held in place by the cement which holds said sheets together, the intermediate sheet of the heating unit being shorter than the outer sheets to provide a pocket therebetween, lead-in wires, a device for securing

said lead-in wires cemented in place in the pocket aforesaid, the ends of the resistance wire being secured to the ends of the lead-in wires, and the end portions of the wires being imbedded in the cement by which the device for securing the lead-in wires is held in place. 70

2. An electric heating unit comprising three thin flat rigid sheets of insulating material cemented to each other, a resistance wire extending back and forth between two of said sheets and held in place by the cement which holds said sheets together, the intermediate sheet of the heating unit being shorter than the outer sheets to provide a pocket therebetween, lead-in wires, a device for securing said lead-in wires comprising a strip of insulating material cemented in place in the pocket aforesaid, said strip having a plurality of holes through which the lead-in wires extend, the ends of the resistance wire being secured to the ends of the lead-in wires, and the portions of the wires associated with the strip being imbedded in the cement by which the strip is held in place. 80 85

3. An electric heating unit comprising three thin flat rigid sheets of insulating material cemented to each other, a resistance wire extending back and forth between two of said sheets and held in place by the cement which holds said sheets together, the intermediate sheet of the heating unit being shorter than the outer sheets to provide a pocket therebetween, lead-in wires, a device for securing said lead-in wires comprising a strip of insulating material cemented in place in the pocket aforesaid, said strip having a plurality of holes through which the lead-in wires extend, said strip having tongue portions for confining the resistance wire near the ends thereof, the ends of the resistance wire being secured to the ends of the lead-in wires, and the portions of the wires associated with the strip being imbedded in the cement by which the strip is held in place. 90 95 100 105

In testimony whereof, I have hereunto signed my name.

RENÉ G. HARE.
